UNITED STATES PATENT OFFICE.

ALBERT D. MARBLE, OF OKLAHOMA, OKLAHOMA TERRITORY.

GUN-STOCK AND CARTRIDGE-MAGAZINE.

SPECIFICATION forming part of Letters Patent No. 746,859, dated December 15, 1903.

Application filed November 19, 1902. Serial No. 132,005. (No model.)

To all whom it may concern:

Be it known that I, ALBERT D. MARBLE, a citizen of the United States, residing at Oklahoma city, in the county of Oklahoma and Territory of Oklahoma, have invented a new and useful Gun-Stock and Cartridge-Magazine. Therefor, of which the following is a specification.

This invention relates to gun-stocks and cartridge-magazines used in connection therewith.

The object of the invention is in a ready, simple, thoroughly-feasible, and practical manner to adapt a gun-stock for carrying in a limited space a large number of rounds of ammunition and disposing the ammunition in such manner as to be readily accessible when needed; furthermore, to obviate any rubbing off or removal of the lubricant where the magazine holds ball-cartridges; furthermore, to dispose the cartridges in such manner in the stock as to effect balancing of the barrel, and thus aid in steadyng the firearm when aiming at an object; furthermore, to provide a gun-stock with a magazine in which the cartridges are constantly exposed, but which while operating positively to prevent accidental loss of the cartridges will present no objectionable resistance to their removal when needed for use.

With these and other objects in view, as will appear as the nature of the invention is better understood, the same consists in the novel construction and combination of parts of a magazine gun-stock, as will be herein-after fully described and claimed.

In the accompanying drawings, forming a part of this specification, and in which like characters of reference indicate corresponding parts, there is illustrated one form of embodiment of the invention capable of carrying the same into practical operation, it being understood that the elements therein exhibited may be varied or changed as to shape, proportion, and exact manner of assemblage without departing from the spirit thereof.

In the drawings, Figure 1 is a view in section of the rear portion of a gun-stock, a portion thereof being broken out to show the improvements of this invention applied thereto. Fig. 2 is a view in rear elevation showing the

construction of the butt-plate. Fig. 3 is a view in transverse section taken on the line 3-3 of Fig. 1. Fig. 4 is a perspective detail view of the supplemental magazine. Fig. 5 is a detail view in elevation of the rear portion of the stock.

The stock 1, which may represent either that of a shotgun or rifle, is provided with a bore 2, in which is housed a tube 3, within the inner end of which is fixed a spring-pressed plunger 4. Normally housed within the tube 3 is a magazine 5, shown in this instance as composed of three split tubes 6, secured at their points of juncture in any preferred manner, as by being soldered or brazed that end of the magazine which will be the outer one in use having secured to it a disk 7 of a size to fit within the tube 3. The split tubes or cartridge-holders 6, of which there are shown three in this instance, although a greater number may be employed if found necessary or desirable, are constructed of thin sheet metal, preferably of brass, and normally the lips of the slots are separated a sufficient distance, owing to the resiliency of the metal of the tubes, to permit of the contained cartridges, when the open ends of the tubes are turned downward, to escape; but when placed within the tube 3 the said holders will be slightly compressed, thereby to prevent the cartridges from moving about when the firearm is handled.

The spring 8, that actuates the plunger 4, is secured at one end to the tube 3 and at its other end to the plunger 4 and has a range of movement sufficient to force the supplemental magazine 5 a sufficient distance beyond the butt-plate 9 to permit of its being readily grasped and removed.

The butt-plate 9 is provided with an orifice 10, disposed in alignment with the tube 3, and this orifice is normally closed by a plate 11, fitting in a recess formed in the end of the stock, said plate being held in position for pivotal movement by one of the screws 12, that holds the butt-plate upon the stock. The outer side of the plate is provided with a lip 13, adapted to rest in a recess 14, cut in the stock, thus to be out of the way, the function of the lip being to enable the operator to move the plate outward to free the opening 10 when the magazine is to be removed.

To hold the plate 11 against working outward, and thus releasing the magazine 5, a friction device is employed, consisting of a plug or piece of rubber 23, seated in the stock 5 and bearing against the said plate, as clearly shown in Figs. 2 and 5.

Having thus described the invention, what I claim is—

1. The combination with a gun-stock, of a tube housed therein, a spring-pressed plunger secured to the inner end of the tube, a cartridge-magazine comprising a plurality of split tubes, a head to which the tubes are secured, and means for holding the magazine within the tube.

2. The combination with a stock having a bore or housing, of a transversely-compressible cartridge-receiving magazine removably fitted in the bore or housing, and adapted for compression by the walls thereof.

3. The combination with a stock having a bore or housing, of a magazine comprising a group of connected transversely-compressible

cartridge-receiving tubes, removably fitted in the bore or housing, and adapted for compression by the walls thereof.

4. The combination with a gun-stock, of a tube carrying a spring-pressed plunger, and a magazine adapted to be disposed within the tube, the magazine comprising a plurality of split tubes which are normally of greater internal diameter than the rims of the cartridges to permit the latter to be readily removed when the magazine is withdrawn from the tube but which are adapted to be compressed when placed within the tube thus to prevent any rattling or movement of the cartridges.

In testimony that I claim the foregoing as my own I have hereto affixed my signature in the presence of two witnesses.

ALBERT D. MARBLE.
